UNITED STATES PATENT OFFICE

158,916

HOMOGENIZER

Walter Watling, Chicago, Ill.

Application February 11, 1949, Serial No. 811

Term of patent 7 years

(Cl. D23--1)

To all whom it may concern:

Be it known that I, Walter Watling, a citizen of the United States, residing at Chicago, in the county of Cook and State of Illinois, have invented a new, original, and ornamental Design for a Homogenizer, of which the following is a specification, reference being had to the accompanying drawing, forming part thereof.

Figure 1 is a side elevational view of a homogenizer embodying my new design.

Figure 2 is a front elevational view thereof.

Figure 3 is a rear elevational view thereof.

I claim:

The ornamental design for a homogenizer, substantially as shown.

WALTER WATLING.
